UNITED STATES PATENT OFFICE.

FRANKLIN W. BROOKS, OF WASHINGTON, DISTRICT OF COLUMBIA.

CAR-SEAL.

SPECIFICATION forming part of Letters Patent No. 643,345, dated February 13, 1900.

Application filed May 13, 1899. Serial No. 716,661. (No model.)

To all whom it may concern:

Be it known that I, FRANKLIN W. BROOKS, a citizen of the United States, residing at Washington, in the District of Columbia, have 5 invented certain new and useful Improvements in Car-Seals; and I do hereby declare the following to be a full, clear, and exact description of the invention, such as will enable others skilled in the art to which it appertains 10 to make and use the same.

My invention relates to certain new and useful improvements in car-seals, and particularly to that class composed of sheet metal, (preferably tin.)

15 It has for its object to provide a seal simple and economic in construction and having its parts and the wire shackle readily assembled and secured together in such homogeneity as to secure the greatest amount of protection available in seals of this class.

20 With these ends in view my invention consists of two sheet-metal pieces struck up by dies and adapted to fit one within the other and with an intermediate space for one or two 25 disks or anvils of material having yielding disks or anvils of material having yielding 30 resistant properties—such as thin sheet-lead, felt, cardboard, or the like—the two body portions of sheet metal being permanently connected at their edges and capable of final compression and impression by dies in an ordinary hand-press, all as will be hereinafter more fully set forth.

In order that those skilled in the art to which 35 my invention appertains may know how to make and use the same, I will describe the construction, method of assembling, &c., referring by letters to the accompanying drawings, in which—

40 Figure 1 represents a top or plan view of the bottom half of my improved seal; Fig. 2, a similar view of the top or upper portion of the seal; Fig. 3, a section on the line *x x* of Fig. 1 with the anvil in position; Fig. 4, a section on the line *y y* of Fig. 2 with the anvil 45 in position; Fig. 5, a diametric section through both parts of the seal assembled ready to be secured by turning down the overlapping flange or wall of the lower portion and with a single anvil located in the space between 50 the two halves of the seal. Fig. 6 is a similar view showing the overlapping flange or wall turned down and the two parts thus se-

curely connected. Fig. 7 is a similar view to Fig. 6, but showing the shackle-channel in the rim-flanges rather than in the walls of 55 the crowns, as shown at Figs. 5 and 6. Fig. 8 is a similar view to Figs. 5, 6, or 7 after the seal has been subjected to compression by a hand-press to flatten the same, embed the shackle ends in the anvil, and to produce any 60 desired impression or character upon either or both of the exposed crown-surfaces of the seal. Fig. 9 is a top or plan view of the seal after compression and showing in dotted lines the location of the ends of the wire shackle 65 within the seal. Fig. 10 is a plan view showing a modification in the design or shape of the seal. Fig. 11 is a horizontal section on the line *z z* of Fig. 8. Fig. 12 is a plan view showing one way of forming the ends of the 70 shackle-wire; Fig. 13, a similar view of a modified form for the ends of the shackle-wire, and Fig. 14 a similar view of another modification in the form of the ends of the shackle.

Similar letters and figures of reference indicate like parts in the several figures of the drawings.

75 A and B are the two parts of the seal, and for convenience of description I shall designate the part A as the "top" and the part B as the "bottom." Each of these parts is of hat form, as clearly shown in Figs. 3, 4, 5, 6, and 7, and embodies a crown *a*, a rim *b*, and a flange *c*.

80 Channels or openings 1 are formed in the flanges *c*, as shown at Figs. 3, 4, and 7, or in the vertical wall of the crowns *a*, as shown at Figs. 5 and 6, to receive the hooked, crimped, or knotted ends of the shackle-wire C. The top hat portion A is placed within the bottom portion B, so that the flange *c* of the portion A will rest upon the rim *b* of the lower portion B, as clearly shown at Figs. 5, 6, and 7, and a single thin disk or anvil D, of sheet-lead, felt, or other suitable material, may be 90 interposed between the flange *c* and the rim *b*, as shown at Figs. 5, 6, and 8, or such a disk or anvil may be placed within each crown, as shown at Figs. 3, 4, and 7, and after the parts have been thus assembled the flange *c* of the 100 bottom portion B is turned over by suitable dies in a press, as shown at Figs. 6 and 7, and, if desired, one end of the shackle-wire may be placed in position before this operation,

which will hold said wire sufficiently to prevent it from accidentally falling out without in any manner preventing the subsequent insertion of the other end of said shackle-wire, 5 and in this condition the seals are ready for the market.

When the two portions of the seal are being struck up under dies, any desired characters or letters may at the same time be impressed 10 upon one or both of the crowns *a*, and any desired characters or letters may likewise be impressed upon either or both crowns by the hand-press employed to crush the crowns and permanently lock the wires in place, as shown 15 at Figs. 8, 9, 10, and 11.

When the shackle-channels 1 are formed in the vertical wall of the crown *a*, one of said channels may be formed in each crown, as shown at Fig. 5, or both of said channels may 20 be formed in either one or the other of the crowns side by side, as shown at Fig. 6, or a single channel of sufficient length may be made to receive both ends of the shackle-wire, and, as before stated, a single disk or anvil *D* 25 may be interposed, as shown at Figs. 5 and 6, or two anvils may be located, one in each crown, as shown at Figs. 3, 4, and 7. In the former case when the seal is crushed or compressed in a hand - press the hooked ends of the 30 shackle-wire will be confined between the disk and the crown *a* of one of the portions of the seal and partially embedded in the disk *D*, and in the latter case the ends of the shackle-wire will be confined between and 35 embedded within the two disks.

The disks or anvils, it will be readily seen, may be punched out of sheet-lead, felt, or other material suitable for the purpose in a manner similar to that employed in the manufacture of ordinary gun-wads, and as either 40 one or both of the anchors or disks are confined between the crown-surfaces of the two-part sheet-metal seal they may be comparatively thin, and by reason of the proportions 45 and method of manufacture they will of necessity be of very slight cost, and as the two parts of the sheet-metal seal are struck up between dies and are formed with the crown, rim, and flange, as described, the metal may 50 be comparatively thin and correspondingly cheap, so that the seal as an entirety may be placed upon the market and used at a price much lower than seals involving a larger amount and more expensive material and requiring 55 to a greater extent hand labor.

While I prefer the forms and details of con-

struction shown and described, I do not wish to be strictly limited thereto, as it is obvious that the profile or cross-section of the two sheet-metal parts of my improved seal may 60 be varied without departing from the spirit of my invention, the generic principle of which rests in a sheet-metal seal composed of two parts preliminarily secured together and having confined between them a shackle-anchor composed of material affording a yielding resistance and of a thickness less than the space between the interior faces of the sheet-metal parts, so that not only may the shackle-wire be embedded within and locked 65 by said anchor, but that the said anchor shall constitute an anvil, upon which any suitable impression may be made upon the exposed flat surfaces of the seal.

What I claim as new, and desire to secure 75 by Letters Patent, is—

1. A seal composed of two unbroken sheet-metal parts secured together at their edges, either or both of said portions provided with entrances for the shackle-wire, and adapted 80 to receive impressions on their flat exposed surfaces, an interposed confined and concealed anchor or anvil having the characteristic of yielding resistance, and smaller in cross-section than the space between the interior faces of the sheet-metal parts, and a shackle-wire having its ends returned or bent and embedded in the face of the anchor or anvil and confined between the interior faces of the sheet-metal parts, substantially as hereinbefore set forth. 85

2. A seal embodying in its organization two hat-shaped sheet-metal portions *A* *B* joined by overlapping flanges and formed with shackle-entrances and having continuous exterior surfaces adapted to receive impressions, an interiorly confined and concealed anchor or anvil, smaller in cross-section than the space between the interior faces of the sheet-metal parts and having inherent yielding resistance properties, and a shackle-wire having its ends bent and embedded in the face of the anchor or anvil and confined between the interior faces of the sheet-metal parts *A*, *B*, substantially as hereinbefore set forth. 95

In testimony whereof I affix my signature in presence of two witnesses.

FRANKLIN W. BROOKS.
